UNITED STATES PATENT OFFICE.

EDWIN J. BLOOD, OF CHICAGO, ILLINOIS.

HAME-TUG.

SPECIFICATION forming part of Letters Patent No. 247,501, dated April 26, 1881.

Application filed January 29, 1881. (Model.)

To all whom it may concern:

Be it known that I, EDWIN J. BLOOD, of the city of Chicago, in the county of Cook and State of Illinois, have invented certain new and useful Improvements in Hame-Tugs, which are fully set forth in the following specification, reference being had to the accompanying drawings, in which—

Figure 1 is an outside elevation of my improved hame-tug. Fig. 2 is a longitudinal section of the same on the line $x x$ in Fig. 1. Fig. 3 is a transverse section on the line $y y$, Fig. 1, looking to the left. Fig. 4 is an enlarged detailed section, on the line $x x$, Fig. 1, of one bridge with the clutch in position for detachment. Fig. 5 is an enlarged perspective view of the clutch.

The same letters denote the same parts in all the figures.

My invention relates to means for fastening the traces of harness to the hames; and it consists in the several devices and combinations of devices, which will be fully set forth herein-after, and pointed out definitely in the claims, the object being to provide a perfectly secure attachment adjustable at different lengths, more simple, convenient, and economical than those ordinarily in use.

In the drawings, A denotes a frame, of metal or other suitable material, provided at the rear end with the guards a and a' , for confining the forward part of the trace B in a direction parallel to that of the frame, the outer guard, a , being a little forward of the inner, a' , and each being bent at the ends, so as to stand off a little from the rest of the frame, and thus allow the trace, when in use, to lie a little nearer to the horse's body than the frame, and to be passed forward and downward between the two bars for the purpose of bringing it into position for attachment and detachment. The frame has also near this end the customary loops a^2 on its edges. At the forward end the frame terminates in a hook, C, for attaching it to the hame.

A guard-hook, C', of corresponding curvature, is set within the tug-hook C, its opening being toward the closed part of C and its closed part bridging the opening of C, so as to form with it a completely-closed loop, and to constitute a lining for the interior of C, so that the latter will not come in contact with the hook on the

hame. The guard-hook C' has a short shank, c' , which is affixed to the inner face of the shank of C by a screw or rivet.

It is found that the wear in attachments of this class comes principally on the inner face of the tug-hook, where it is in contact with the hook of the hame, and by interposing the guard-hook C' in this place I bring this wear upon a part readily detached and replaced, and thus avoid any necessity of throwing away the parts that are still serviceable.

The two side bars, A', of the frame A are connected at convenient distances by cross-bars or bridges D, each nearly in the form of a quarter-cylinder having its quadrantal convex surface forward and its lower edge forward of the upper and about on a level with the tops of the side bars. These bridges rest at their ends on supports d , raised above the upper edges of the side bars, A', and extending a little way back of the bridges. From the facing sides of these supports lips or stops d' project a short distance inwardly—that is, each toward the opposite side bar. Between the upper of the bridge D and the forward end of the lip d' there is a little space, just enough to admit easily the thickness of the arched portion E' of the clutch E, which is fastened to the forward end of the trace B. The entire frame A, except the guard-hook C', may be made in a single casting. The forward edge of each lip d' is curved to correspond to the curvature of E', which is bent nearly in the form of a half-circle or hollow half-cylinder. From the base of this arched portion extend backward a pair of straight bars, e, which support between their farther ends a cylindrical cross-bar, e', around which the forward end of the trace is fastened, in the usual way of fastening a strap on the frame of a buckle. A tongue, e^2 , extends backward from the rear surface of this cross-bar, and is inserted between the thicknesses of the trace, which is thus kept from turning on the bar.

To attach the trace to any one of the bridges D, the clutch must be brought into such a position that the diameter or span of its arched portion E' shall incline backward from a perpendicular and nearly at an angle of forty-five degrees, in which position the upper edge of E' can be slipped between the forward ends

of the lips d' and the upper edge of the bridge D and hooked on the latter. The trace being then drawn between the guards a and a' into a direction parallel with that of the side bars, 5 A', the arched portion E' of the clutch will by the same motion be turned downward and forward, so as to fit on the arched surface of the bridge D. In this position the clutch will be incapable of being detached from the bridge, 10 any backward pull bringing the convexity of the arch against the forward ends of the lips d' , and any forward thrust (if such were possible) setting the base of the arch firmly against the back of the bridge. If, now, it be desired 15 to detach the trace, it must be drawn forward between the guides until slack enough has been obtained to turn it so far that the span of the arch E' shall pass a perpendicular and make an angle of nearly forty-five degrees. 20 The arch will then lose its hold on the bridge, and can be slipped down between the bridge and the lip.

Obviously by detaching the clutch from one bridge and attaching it to another the distance from the hame to the whiffletree will be 25 lengthened or shortened, as the case may be, and the number of bridges and length of the frame A may be adapted to the desired number and range of such adjustments.

30 What I claim as my invention, and desire to secure by Letters Patent, is—

1. In a hame-tug, a frame having longitudinal bars provided with a connecting-bridge inclined downward and forward, and convex on its forward side, and with an inwardly-projecting lip arranged on each bar a little behind the bridge, and having its forward and lower side re-entrantly curved similarly to the bridge, in combination with a clutch provided at its forward end with a hollow cylindrical portion similarly curved, substantially as and for the purpose described. 35

2. A tug-hook, in combination with a guard-hook of similar curvature arranged within it reversely and detachably connected with it, 40 substantially as and for the purpose described.

3. The frame A, provided with the bridges D and lips d' , in combination with the clutch E, provided with the hollow cylindrical portion E', all constructed, arranged, and operating substantially as and for the purpose described. 45

4. The clutch E, provided with the hollow cylindrical portion E', cross-bar e' , and tongue e^2 , all constructed, arranged, and operating 50 substantially as and for the purpose described.
